[57] CLAIM

The ornamental design for child's light switch extension, as shown and described.

DESCRIPTION

FIG. 1 is a top plan view of a child's light switch extension showing my new design;

FIG. 2 is a side elevational view thereof with a light switch and switch plate shown in broken lines for illustrative purposes only; and

FIG. 3 is a second top plan view thereof with a light switch and switch plate shown in broken lines for illustrative purposes only.

FIG. 1

FIG. 2

FIG. 3
